UNITED STATES PATENT OFFICE.

ELIZABETH BARRY, OF PORTLAND, OREGON.

DOLL.

Application filed September 22, 1921. Serial No. 502,375.

To all whom it may concern:

Be it known that I, ELIZABETH BARRY, a citizen of the United States, residing at Portland, in the county of Multnomah and 5 State of Oregon, have invented a new and useful Doll, of which the following is a specification.

The device forming the subject matter of this invention is a doll, and the invention 10 aims to provide a doll, the garments of which may be removed readily for cleaning.

Another object of the invention is to provide a head of novel and improved form.

15 A further object of the invention is to provide novel means for fashioning the hair, ears and the like.

It is within the province of the disclosure to improve generally and to enhance the 20 utility of devices of that type to which the invention appertains.

With the above and other objects in view, which will appear as the description proceeds, the invention resides in the combination and arrangement of parts and in 25 the details of construction hereinafter described and claimed, it being understood that, within the scope of what is claimed, changes in the precise embodiment of the 30 invention shown can be made without departing from the spirit of the invention.

In the accompanying drawings:—

Figure 1 shows in front elevation, one 35 form of doll constructed in accordance with the invention; Figure 2 is a rear elevation; Figure 3 is a longitudinal section on the line 3—3 of Figure 1; Figure 4 is a front elevation of the doll, certain of the garments being removed; Figure 5 is a 40 rear elevation of the doll when the doll is in the condition shown in Figure 4; Figure 6 is a front elevation of the doll, the drawers, gloves and cap having been added; and Figure 7 is a cross section taken approximately on the line 7—7 of Figure 5.

The doll forming the subject matter of this invention includes a body 1 having legs 2 and arms 3. Stockings 4 are mounted on the legs 2. A mass of yarn, indicated at 50 5, is threaded into the lower ends of the stockings 4 and into the legs 2 to form the heel of the foot, the leg being surrounded by a circumscribing band of yarn 6 or the like, to form the ankle. An upper 55 standing loop 7 of yarn or the like is stitched into the stocking 4 and in the leg

2 to simulate a buckle, the lower ends of the loop 7 being connected to the band 6.

An underskirt 8 may be mounted on the body 1, the upper end of the skirt preferably being stitched at 9 to the body. The skirt 8 is caught together or stitched, as shown at 10 in the crotch, to simulate a pair of drawers.

Gloves 11 are mounted on the arms 3 and 65 may be circumscribed by a band 12 of stitching or the like, engaging the arms 3, and simulating a bracelet. The body 1 and the arms 3 may be encased in a jacket 14, if desired.

70 The body, the legs and the arms of the doll may include a casing 15 of cloth or the like, containing a stuffing 16 of any desired sort, such as cotton. The casing 15 is closed together and stitched at its upper end 75 as indicated at 17 in Figure 3.

The head of the doll comprises a cover 18 and a rubber ball 19 within the cover, the cover being made of any suitable cloth and being contracted and stitched to the body 80 as shown at 21 to form the neck. The upper end of the cover 18 of the head may be contracted and stitched together as shown at 20 in Figure 5.

A guimpe 22 extends across the chest and 85 has flaps 23 extended downwardly on the back as shown in Figure 5. The lower edge of the guimpe is stitched at 24 to the body, the inner edges of the flaps 23 of the guimpe being stitched as indicated at 25 to the body. 90 The guimpe may be embroidered, as shown at 26, to imitate a neck chain.

The numeral 27 denotes a flexible element, preferably in the form of a braid, the intermediate portion of the flexible element being secured at 28 to the cover 18 of the head, the ends of the flexible element depending, as shown in Figure 2 to represent braided hair. The front portion of the cover 18 of the head may be slit to form a rib or 100 strip 29 secured at both ends and extending from the front to the rear. A mass of yarn or like flexible material is run underneath the rib 29 and is extended downwardly along the sides of the head, the ends of the 105 mass of yarn being embroidered as at 31 into the cover 18 to imitate the ears. It is to be observed that the rib 29 not only serves to hold the yarn 30 in place, but serves, also, to define the part in the hair, 110 represented by the yarn 30. The features 32 may be embroidered or marked otherwise

on the cover 18 of the head. The head may be surmounted by a cap 33 held in place by a throat latch 34 in the form of knotted cords or the like.

5 Having thus described the invention, what is claimed is:

1. In a doll, a head comprising a covering having a strip secured at the ends thereof and extending from the front towards the 10 back, flexible material extended beneath the strip to simulate hair, the strip also defining a part in the hair.

2. In a doll, a head comprising a covering having a strip secured at the ends thereof 15 and extending from the front towards the back, and flexible material extended beneath the strip to simulate hair, the strip also defining a part in the hair, the ends of the flexible material being connected to the head 20 covering at the sides of the head to form representations of ears.

3. A doll comprising a head including a

covering having a strip secured at its ends thereto and extending from the front toward the back and flexible material extended beneath the strip to simulate hair, the strip defining a part in the hair, and the ends of the flexible material being worked into the covering to form enlargements representing ears. 25

4. In a device of the class described, a doll including a head comprising a covering having a slit therein; and a flexible element secured intermediate its ends to the covering by passage through said slit and depending from its point of connection with the covering, to define braids of hair. 30

In testimony that I claim the foregoing as my own, I have hereto affixed my signature in the presence of two witnesses.

ELIZABETH BARRY.

Witnesses:

FRANCES CHAMPAGNE,
C. A. KRESSMANN.
